UNITED STATES PATENT OFFICE.

GEORGE N. PHELPS, OF BROOKLYN, ASSIGNOR OF ONE-HALF TO HOWARD S. NYMAN, OF NEW BRIGHTON, NEW YORK.

ORE-ROASTING FURNACE.

SPECIFICATION forming part of Letters Patent No. 446,996, dated February 24, 1891.

Application filed March 24, 1890. Serial No. 345,038. (No model.)

To all whom it may concern:

Be it known that I, GEORGE N. PHELPS, of Brooklyn, Kings county, New York, have invented a new and useful Improvement in 5 Ore-Roasting Furnaces, of which the following is a specification.

My invention relates to furnaces for roasting ores, and has for its objects to thoroughly roast the ore, prevent deoxidation of the material, and economize fuel.

To this end my invention consists in the furnace, as hereinafter described and claimed. By my device these objections are obviated.

In the accompanying drawings, Figure 1 is 15 an elevation of my device in vertical section. Fig. 2 is a plan view.

Referring to the drawings, A indicates a retort of earthenware, metal, or other suitable material, open at the top for the reception of 20 the material to be roasted, as well as for the escape of the heated air passing through it. The retort A is located in an oven B, as shown, so as to be surrounded by the fuel gases in a high state of combustion, and rests upon a 25 base C, which in turn is located upon the top of a pit D. The retort A is separate from the base C, so that it can be removed, if desired, and repaired or another substituted in its place. Within the oven B is also located a super- 30 heater E, which is here shown in the shape of a cylinder, and through which air is forced and heated and carried to the retort A.

While I have shown but one retort, oven, and superheater, any number may be employed in accordance with the quantity of material to be roasted.

It will be seen that the oven B is located between the furnace F and chimney G, so that the products of combustion must pass by 40 means of flue f into and through oven B, heating-retort A and superheater E, and thence by flue f' into chimney G.

In addition to the heating of retort A, the material therein is subjected to the action of 45 heated air, as follows: The base C is formed with an annular chamber C', having two valves a b connected together and forming a double valve, the valve a being perforated or otherwise apertured and closing the lower end 50 of retort A, and the valve b closing the bottom of chamber C'.

The chamber C' is connected with the superheater E by means of a pipe C''.

H indicates an air-supply pipe, by means of which air is forced in any suitable manner 55 through the superheater E, pipe C'', chamber C', and through perforated valve a up retort A. The superheater is filled with nails a or other suitable material in small pieces, so that the air will percolate through it and become 60 heated. The material to be roasted is placed in retort A through its top. It will be seen that air forced into superheater E by pipe H will become highly heated, and, passing through pipe C'', chamber C', and perforated valve a, 65 will ascend up through the material in retort A and oxidize the same. In this way the material is roasted not only by the action of highly heated air passing through it, but also by having the retort surrounded by the fuel- 70 gases in a high state of combustion passing from the oven to the chimney. The material in the retort is gently agitated by stirrers h on a shaft K, revolved by any suitable mechanism—as, for example, a bevel-gearing I. 75 The shaft K is mounted at its lower end in a bearing K', and at its top in a stuffing-box M, so that it can revolve freely. The shaft K and stirrers h are hollow, and are kept cool by means of a circulation of cold water passing 80 into shaft K from pipe i, located therein and connected with a water-supply. The water becoming heated passes off through outlet k. By the means described the material to be roasted is thoroughly subjected to the ac- 85 tion of heat, the products of combustion are thoroughly utilized without any deleterious effect on the ore, and the process of roasting is hastened with a comparatively small consumption of fuel. When the material has 90 been roasted, the valves a b are swung into the pit D and out of the way by means of an arm L, operated by any suitable mechanism, and the material drops into the pit.

While my device may be used for roasting 95 any kind of ore, it is especially adapted for chrome iron ore, which is especially difficult to oxidize.

Having described my invention, what I claim is—

1. In an ore-roasting furnace, the combination, with a retort, of a pit, a chamber located

between the bottom of the retort and the pit and opening into the retort and pit, a double valve having an apertured upper portion and closing the top and bottom of the chamber beneath the retort, and a superheater connected by an air-supply pipe with the chamber beneath the retort, the superheater and retort being located in an oven connected at its top with a furnace and at its bottom with a chimney, substantially as shown and described.

2. In an ore-roasting furnace, a substantially vertical retort inclosed in an oven connected at its top with a furnace and at its bottom with a chimney, a pit, a hot-air chamber located beneath the retort and opening into the retort and pit, means for supplying hot air to the hot-air chamber, and a double valve having an upper apertured portion which closes the bottom of the retort and a lower portion which closes the opening between the hot-air chamber and pit, substantially as shown and described.

3. An ore-roasting furnace consisting of a substantially vertical retort inclosed in an oven connected at its top with a furnace and at its bottom with a chimney, a hollow stirring device located in the retort and having water supply and discharge pipes, a superheater inclosed in the oven, a hot-air chamber located beneath the retort, an air-supply pipe connecting the superheater with the hot-air chamber, a pit located beneath the hot-air chamber, and a double valve having an apertured upper portion closing the bottom of the retort and top of the hot-air chamber and a lower portion closing the bottom of the hot-air chamber and the top of the pit, substantially as shown and described.

In testimony whereof I have hereunto subscribed my name.

GEORGE N. PHELPS.
